U.S. Cl. D14—6

Fig. 1.

Fig. 2.

Fig. 3.

Fig. 4.

Fig. 5.

FIG. 1 is a top plan view of a dimmer switch pedal, showing my new design.

FIG. 2 is a right hand side elevational view thereof.

FIG. 3 is a bottom plan view thereof.

FIG. 4 is a rear end view thereof.

FIG. 5 is a front end view thereof.

The left hand side elevational view would be a mirror image of the right-hand side elevational view of FIG. 2.

The dimmer switch, shown in broken lines in FIG. 2, is included for illustrative purposes only.

I claim:

The ornamental design for a dimmer switch pedal, as shown and described.
